UNITED STATES PATENT OFFICE.

HENRY P. GONSOULAND, OF OAKLAND, CALIFORNIA.

WATER-HEATING APPARATUS.

1,178,445.

Specification of Letters Patent.

Patented Apr. 4, 1916.

Application filed November 2, 1914. Serial No. 869,966.

To all whom it may concern:

Be it known that I, HENRY P. GONSOULAND, a citizen of the United States, residing at Oakland, in the county of Alameda and State of California, have invented certain new and useful Improvements in Water-Heating Apparatus; and I do hereby declare the following to be a full, clear, and exact description of the invention, such as will 10 enable others skilled in the art to which it appertains to make and use the same.

This invention relates to water heating apparatus, designed for use on railroads and one of the principal objects of the invention 15 is to provide an apparatus for heating water for use in the wash room and for flushing the toilet bowl.

Another object of the invention is to provide a water heating apparatus for railway 20 trains, in which steam from the locomotive is used for heating the water for washing purposes and for flushing the toilet bowl.

These and other objects may be attained by means of the construction illustrated in 25 the accompanying drawing, in which the figure is a view in elevation and partial section of a water heating apparatus made in accordance with this invention.

Referring to the drawing, the numeral 1 30 designates the water tank and 2 is the pipe which leads ordinary cold water into said tank. Leading from the tank 1 is a discharge pipe 3 which communicates with a heater 4. The water heater 4 has a steam 35 inlet pipe 5 with a valve 6, said pipe 5 leading into the heater 4 and connected up to a coil 7 extending from near the top to near the bottom of said heater, and terminating in a return pipe 8 which leads to the 40 boiler of the locomotive. In the heater 4 is a float 9 secured centrally to a rod 10, the upper portion 10^c of which is adapted to slide in the pipe 3, and the lower portion 11 of which is adapted to slide in a pipe 12 45 which leads to the toilet bowl 13. The top and bottom walls of the heater 4 are formed to provide valve seats 10^a and 11^a, respectively. The portion 10^c is provided at a point above the float 9 with a valve 10^b, and

the portion 11 is provided at a point below 50 the float 9 with a valve 11^b.

From the end of the heater 4, a hot water pipe 14, having a vertical branch 15 and a horizontal branch 16, leads up through a vertical pipe 17 to a faucet 18 disposed above 55 the wash bowl 19, said faucet 18 being provided with a valve 20. The bowl 19 is provided with a waste pipe 21 which leads to the toilet bowl 13. The pipe 12 is provided with a flushing valve 22. 60

The operation of the invention may be briefly described as follows:

Steam may be admitted to the coil 7 through the steam pipe 5 to heat the water which is discharged into the heater 4 65 through the pipe leading from the tank 1. When the water in the heater 4 rises to a certain height, the float 9 will seat the valve 10^b and unseat the valve 11^b, cutting off the supply of water to the heater and permitting 70 the heated water to flow to the bowl 13 on the opening of the valve 22. When the level of water in the container falls below a certain height, the float 9 will seat the valve 11^b and unseat the valve 10^b permitting 75 water to enter the heater 4. The steam coil 7 will heat the water and it may be used in the wash bowl 19 and for flushing the bowl 13.

Various changes may be made in the details of construction without departing from the spirit and scope of the invention as defined in the claim. 80

What is claimed is:-

A water heating apparatus for toilet and 85 wash bowls, comprising a heater having side, top and bottom walls, said top and bottom walls being provided with inlet and outlet openings, respectively, and with valve seats surrounding said openings, a feed pipe communicating with the inlet opening, a discharge pipe communicating with the outlet opening, a rod located within the heater and having its ends disposed in said pipes, a float carried by said rod, a valve secured to 90 the rod above the float, another valve secured to the rod below the float, a heating coil located within the heater, a steam feed pipe 95

connected to the upper end of the coil, a return feed pipe connected to the lower end of the coil, said discharge pipe communicating with the toilet bowl, another pipe communicating with the heater and with the wash bowl, and valves in the steam feed pipe, discharge pipe and said other pipe.

In testimony whereof I affix my signature in presence of two witnesses.

HENRY P. GONSOULAND.
